UNITED STATES PATENT OFFICE.

JOSEPH V. RICHARDSON, OF GOSHEN, INDIANA, ASSIGNOR TO THE SUPERIOR LADDER CO., OF GOSHEN, INDIANA.

TENONING-MACHINE.

1,193,612.

Specification of Letters Patent.

Patented Aug. 8, 1916.

Application filed April 21, 1915. Serial No. 22,845.

To all whom it may concern:

Be it known that I, JOSEPH V. RICHARDSON, a citizen of the United States, residing at Goshen, in the county of Elkhart and State of Indiana, have invented a new and useful Tenoning-Machine, of which the following is a specification.

This invention relates to machines particularly designed for turning or tenoning 10 the ends of ladder rungs and devices of a similar nature.

One of the objects of the invention is to simultaneously turn or tenon both ends of a rung, means being employed for gradually rotating the rung as it is passed 15 through the machine and while being acted on by the cutter so that the rung will issue from the machine in a finished state, the operation of turning the ends being accomplished quickly, accurately and neatly.

A further object is to provide a machine of this character which can be adjusted readily for use in connection with rungs or the like of different lengths.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred form of the invention has been shown.

In said drawings: Figure 1 is a plan view 40 of the machine. Fig. 2 is a front elevation thereof. Fig. 3 is an elevation of one end of the machine. Fig. 4 is a section on line A—B Fig. 2. Fig. 5 is a detail view of a finished rung. Fig. 6 is an enlarged section through a portion of one of the tubular shafts and showing the parts mounted thereon, and showing the adjustable connection between one of the rolls and the shaft driving the same. Fig. 7 is a section on line 45 C—D Fig. 6. Fig. 8 is a section through a portion of a modified form of machine.

Referring to the figures by characters of reference 1 designates a frame of any suitable construction, preferably provided with

longitudinal guide rods 2 the ends of which 55 are fixedly secured to the ends of the frame while depending from the middle portions of the lower guides is a hanger 3.

Mounted on the guide rods 2 between hanger 3 and each end of the frame 1 is a 60 slide made up of cross heads 4 and 5 and which cross heads are connected, in any suitable manner, as by means of tie rods 6. The heads 5 of the two slides are provided, adjacent their ends, with interiorly screw 65 threaded bushings 7 and extending through these bushings and loosely through the heads 4 of the slides are parallel adjusting shafts 8. Those portions of the shafts adjacent and within the bushings are screw 70 threaded, as shown at 9 and the shafts are so threaded that when rotated in one direction they will shift the slides toward each other whereas, when rotated in the opposite direction they will move the slides apart. 75 The two shafts 8 are journaled at their ends within the ends of the frame 1 and are provided at one end with beveled gears 10 meshing with gears 11 secured to the ends of a transverse shaft 12 journaled upon one end 80 of the frame 1. One end of shaft 12 is provided with a crank 13 or the like whereby said shaft can be rotated readily for the purpose of effecting the described adjustment of the slides. 85

Arranged on the cross heads 4 and 5 of each slide are bearings 14 and journaled within these bearings on each slide is a tubular shaft 15 provided with a pulley 16 or the like. The two tubular shafts 15 extend inwardly toward each other beyond the cross heads 5 of the slides and are provided, at their inner ends with cutter heads 17 of any preferred construction and proportions. 90

The two pulleys 16 are driven by endless 95 belts 18 or the like extending downwardly into engagement with drive pulleys 19 secured to the main or drive shaft 20 of the machine, this drive shaft being journaled within the hanger 3, the ends of the frame 1, 100 and within additional hangers 21 which extend downwardly from the heads 4 and 5 close to the sides of the pulleys 19. Shaft 20 can be driven in any suitable manner, a pulley 22 being preferably provided at one end 105 thereof. The pulleys 19 are feathered on the shaft 20 and the hangers 21 constitute shifting means so that, when the slides are ad-

justed toward or from each other, a corresponding adjustment of the pulleys 19 is effected.

One end of shaft 20 has a worm 23 designed 5 to transmit motion, through a worm gear 24 to an upwardly extending shaft 25, there being a gear 26 loosely mounted on this shaft but which is adapted to be coupled thereto by means of a shiftable clutch member 27 10 which may be operated by means of a lever 28. When the clutch member is in engagement with gear 26, said gear will be coupled to the shaft 25 but, when the clutch member is moved out of engagement with gear 26, 15 the said gear will be left free to rotate on the shaft 25. Gear 26 constantly meshes with a larger gear 29 secured to one end of a shaft 30 which is journaled in the heads 4 and 5, said heads being adapted to slide 20 along the shaft. Secured to the shaft 30 at points between the heads are feeding disks 31 each of which is provided at its periphery with recessed shoulders 32, the corresponding shoulders on the two disks being arranged 25 directly opposite each other. These disks work between the lower ends of angular feed strips 33 which are inclined downwardly and inwardly from the outer portions of the heads 5 and are secured to the said heads so 30 as to move therewith.

Secured to each of the heads 5 close to the inner ends of the feed strips 33 are arcuate supporting strips 34 concentric with the axis of tubular shaft 15 and forming a table. 35 These supporting strips 34 are located directly under and concentric with gripping rolls 35 which are mounted on a shaft 36 extending through and adapted to rotate within the tubular shaft 15. Shaft 36 is 40 journaled at its ends upon the ends of the frame 1 and is provided, at one end, with a gear 37 constantly meshing with a gear 38 secured to the upper end of shaft 25. Rolls 35 are designed to tightly engage and bear 45 downwardly on the stock supplied to the machine so as thus to hold the stock firmly on the supports 34, as hereinafter pointed out.

Each roll 35 is preferably adjustably connected to its drive shaft 36 and one means for effecting this adjustment has been shown particularly in Fig. 6. By referring to this figure it will be seen that a disk 42 is keyed to the shaft 36 and has openings 43 through 55 which bolts 44 extend loosely into one face of the roller 35, this roller being mounted for rotation on a tubular sleeve 45 secured in one end portion of an arm 46. The bolts 44 are free to work within the openings 43 and, 60 consequently, the roller 35 is free to move to a position where it is eccentrically disposed relative to shaft 36 although being continuously driven by said shaft through the disk 42 and the bolts 44, as will be obvious. Arm 65 46 is pivotally mounted upon one of the rods

2 and has a laterally extending ear 47 overhanging a bracket 48 extending from the adjacent head 5. A bolt 49 extends upwardly from this bracket and through the ear 47 and mounted on this bolt is a coiled spring 50 which thrusts downwardly on the ear 47. Thus a constant pressure is exerted upon the arm 46 with the result that the sleeve 45 presses the roller 35 downwardly to a position where it is eccentrically disposed relative to the shaft 36. The roller 35, however, is free to move upwardly against the action of spring 50 without, however, interfering with the transmission of motion from the shaft 36 through disk 42 to the 70 roller 35. 75 80

A delivery table preferably made up of opposed angle strips 39, is preferably inclined downwardly and outwardly from the machine, the inner ends of the strips being 85 located where they can receive the stock as it is delivered from the supporting strips 34 in a finished condition.

In using the machine the slides are adjusted toward each other by means of the 90 mechanism hereinbefore described so as thus to bring the cutter heads the desired distances apart. The lower feeding or carrying disks 31 are likewise adjusted along their shaft 30 so as to engage the stock at 95 points between its ends and the upper feeding or grippings rolls are adjusted to assume positions close to the table or supporting strips 34 which are located directly under the cutter heads. When shaft 20 is in 100 motion, motion is transmitted therefrom through the belts 18 to pulleys 16 with the result that the cutter heads are rotated at a high speed. The worm 23 and gear 24 constitute speed reducing means and motion is 105 transmitted therethrough from shaft 20 to shaft 25 which, in turn, constantly transmits motion through the gears 37 and 38 to the shaft 36 on which the upper carrying or gripping rolls 35 are mounted. The rods or 110 other stock to be acted on are placed on the inclined feed strips 33 and will be supplied by gravity, one at a time, to the rotating disks 31. As these disks revolve in the direction indicated by the arrow in Fig. 4, the 115 shoulders 32 thereof will successively engage the rods and lift them onto the supporting strips 34 where they will be gripped by the spring pressed rolls 35 and forcibly rolled along the strips 34 to the delivery strips 39. 120 During this positive rolling of the rods they will be acted on by the rapidly rotating cutter heads with the result that when the rods are discharged from the strips 34 and onto the delivery strips 39, their ends will have 125 been properly turned or reduced. By manipulating the clutch 27, the feeding of stock to the machine can be regulated, the disks 31 only rotating while the clutch is in engagement with gear 26. 130

It is to be understood that various changes may be made in the machine without departing from the spirit thereof, it being possible to use means other than those described for 5 rolling the stock along the table or supporting strips 34 while being acted on by the cutters, thus to properly turn the stock while at the same time feeding it through the machine. Furthermore the use of cutters 10 for simultaneously engaging two ends of each rod greatly expedites the operation of producing tenons on the ends of the rods, and, furthermore, tends to equalize pressure upon the stock so that there is no danger of 15 the stock becoming disarranged while passing through the machine. The rolls 35 will slip upon the stock should the cutter heads require it in order to prevent injury to the stock.

20 The driving mechanism can be varied so as to cause the cutter heads to rotate in either direction desired, it having been found that under some conditions it is desirable to have the cutter heads rotate in one direction so as 25 thus to throw the chips downwardly, whereas in other constructions it is preferred to have the chips thrown upwardly.

Instead of using smooth rolls for rolling the stock along the supporting table, gears 30 can be used for this purpose, the rungs being received between the teeth of the gears and thus carried positively along the table. Where gears are used for this purpose motion can be transmitted directly to them 35 from drive gears as shown in Fig. 8 wherein the feed gears have been indicated at 40 and the drive gears at 41.

What is claimed is:—

1. The combination with a fixed arcuate 40 support and revoluble means for lifting articles one at a time onto the support, of a revoluble cutter concentric with the support, a shaft extending through the cutter, means supported by and revoluble with the shaft 45 for engaging the articles at points between their ends to roll them along the support while acted on by the cutter, and means for pressing said article engaging and rolling means yieldingly against the engaged articles.

2. The combination with an arcuate fixed 50 support, and a shaft concentric with the support, of a revoluble cutter supported by the shaft, an article engaging roller mounted upon and shiftable radially to said shaft,

yielding means for pressing the roller against the articles on the support to roll said articles while being acted on by the cutter, means for transmitting motion from the shaft to the roller independently of such radial movement of the roller, and an additional means for rotating the cutter upon the shaft. 60

3. The combination with arcuate fixed supports and a shaft concentric with the 65 supports, opposed heads slidably mounted on the shaft, means for adjusting the heads toward or from each other, said means being shiftable with the heads, spaced cutters mounted for rotation on the shaft, tubular 70 bearing members fitted loosely on the shaft and mounted to move radially relative thereto, spring pressed supports for the bearing members, rollers journaled on said bearing members for engaging articles and rolling 75 them along the supports, and a coupling between the shaft and each roller for transmitting motion to the roller independently of the radial movement of said roller relative to the shaft. 80

4. The combination with arcuate fixed supports and a shaft concentric with the supports, opposed heads slidably mounted on the shaft, means for adjusting the heads toward or from each other, said means being 85 shiftable with the heads, spaced cutters mounted for rotation on the shaft, tubular bearing members fitted loosely on the shaft and mounted to move radially relative thereto, spring pressed supports for the bearing 90 members, rollers journaled on said bearing members for engaging articles and rolling them along the supports, and a coupling between the shaft and each roller for transmitting motion to the roller independently 95 of the radial movement of said roller relative to the shaft, said coupling including a disk fixedly secured to the shaft and engaging one side of the roller, said disk having openings therein, and means extending loosely 100 through the openings and into engagement with the roller for fastening the roller to the disk.

In testimony that I claim the foregoing as my own, I have hereto affixed my signature 105 in the presence of two witnesses.

JOSEPH V. RICHARDSON.
